UNITED STATES PATENT OFFICE.

EDWARD J. THURBER, OF NEW ORLEANS, LOUISIANA, AND JOHN W. RACKLYEFT, OF DETROIT, MICHIGAN, ASSIGNEES, BY MESNE ASSIGNMENTS, TO NORTHERN ENGINEERING WORKS, OF DETROIT, MICHIGAN, A CORPORATION OF MICHIGAN.

ROTARY STARTER.

1,185,146.

Specification of Letters Patent. Patented May 30, 1916.

Application filed December 17, 1914. Serial No. 877,830.

To all whom it may concern:

Be it known that we, EDWARD J. THURBER, a citizen of the United States of America, residing in New Orleans, parish of Orleans, 5 State of Louisiana, and JOHN W. RACKLYEFT, a citizen of the United States of America, residing at Detroit, county of Wayne, and State of Michigan, have invented certain new and useful Improvements in 10 Rotary Starters, of which the following is a specification, reference being had therein to the accompanying drawings.

The invention relates to rotary starters for internal combustion engines of the type 15 actuated by compressed fluid.

The invention resides in the novel construction of starter whereby the rotary transmission mechanism and the pump are formed as an operative unit; in the provision 20 of a simple and efficient compact unit; in the novel relation of the pump parts to the remaining elements of the structure; and in certain details of construction and combinations and arrangements of parts as will 25 more fully hereinafter appear.

In the drawings, Figure 1 is a central vertical longitudinal section of a starter mechanism embodying the invention; Fig. 2 is an 30 end elevation on the side of the pump, with certain parts broken away; and Figs. 3 to 6 inclusive illustrate certain details of construction.

The starter embodying the invention is primarily designed for use on automobiles 35 and marine engines of the explosion or combustion type, and embodies in a compact structure a fluid-operated rotary motor, a transmission mechanism and a pump.

Referring to the one embodiment of the 40 invention shown in the drawings, 1 designates the casing, divided by a web or partition 2 into two chambers. Within one of the chambers is arranged a rotary motor, while in the opposite chamber is arranged 45 the transmission and clutch mechanism. In the structure illustrated, the casing upon one side of the web is provided with an annular rim 3 that is disposed eccentric with relation to the shaft bearing 4 in the web, 50 while connected to the outer edge of the rim 3 as by screws 5 is a cap plate 6, the latter forming with the rim 3 and the web 2 a chamber for the rotor. The inner peripheral wall 6 of this chamber—as will be noted 55 upon reference to Figs. 1 and 3—is eccentric

to the shaft bearing 4. As the detail construction of the rotor does not form a part of the invention of this application, a description thereof will not be given. The hub 7 of the rotor is keyed at 8 to a sleeve 9 60 that is journaled in the bearing 4 carried by the web 2.

10 is the inlet for the rotor chamber and 11 the exhaust. Upon admission of a compressed fluid to the chamber of the rotor the 65 latter will be set in rotation.

The transmission mechanism is herein shown as of the planetary type. Thus journaled upon stub shafts 12 are pinions 13, which are in constant mesh with an internal 70 or rim gear 14. The latter is carried by a disk 15 which is connected by means of screws 16 to a member 17 that forms a part of a clutch.

18 is the other clutch member which is 75 keyed to a shaft 19 that extends through the sleeve 9.

20 are spring-pressed dogs which in one direction of rotation of the member 17 are adapted to lock said member to the member 80 18, while in the opposite direction of rotation will disconnect the members 17 and 18.

As shown in Fig. 1, the sleeve 9 is provided with a portion that projects within the transmission mechanism housing, and 85 this portion of the sleeve is provided with a pinion 21 that meshes with the pinions 13.

22 is a shaft journaled in a bearing 23 and fixed to rotate with the shaft 19, the shaft 22 in effect forming a continuation of the 90 member 19.

The transmission mechanism chamber is closed by a cap member 24 that is connected by means of screws 25 to the edge 26 of an annular flange 27 extending laterally from 95 the web 2 and concentric with the bearing 4. Detachably connected to the cap of the rotor chamber is a pump housing 28 composed of a ring-shaped portion 29 having a plurality of cylinders 30 (two being shown in the 100 structure illustrated) extending laterally therefrom.

31 are the pistons within the cylinders 30, 32 is the air inlet valve for the cylinder and 33 the exhaust, the latter being provided 105 with a conduit 34 that leads to a suitable storage tank, not shown. The end of each of the piston 35 is provided with a segmental shoe 36 that engages a circular bearing 37, the corresponding ends of the por- 110

tions 36 being spaced from each other and each of the members 36 being provided with a groove 38 within which are arranged retaining rings 39. The member 37 is provided with a bearing 38' eccentric in relation thereto, that is journaled upon a sleeve 39'. As shown in Fig. 1, the shaft 9 is provided with an extension 40 that projects into the pump housing and is splined to the sleeve 39'. Fixed to rotate with the sleeve 39' but free to slide longitudinally thereof is a clutch collar 41 having teeth 42 which are adapted to engage co-operating teeth 43 upon the member 37 and in close proximity to the bearing 38.

44 is a rock arm journaled at 45 in the pump casing and provided with a bifurcated rocker 46 for shifting the clutch collar.

As shown, the end of the pump housing 20 is closed by a plate or cap member 47 having a bearing 48 within which the sleeve is journaled. The shaft 19 therefor is in reality journaled in the bearings 23 and 48. Preferably the outer end of the sleeve 39' is provided with a crank-engaging portion 49 for receiving the usual starting crank, in case the starter becomes inoperative. Normally the crank-engaging portion 49 is closed by means of a cap 50.

30 While the preferred form of the invention has been shown and described, it is not desired to limit the protection to the particular structure illustrated, but the invention is considered of sufficient scope to embody various modifications.

35 What we claim as our invention is:—

1. In a starter, a housing, a rotor and a speed reduction transmission mechanism arranged in said housing, a pump, a shaft alternatively driven by the rotor through said transmission mechanism, and driving the pump independently of said transmission mechanism within the housing for operatively connecting the pump to and disconnecting it from said shaft, and means exterior to the housing for manually controlling the last named mechanism.

2. In a starter, a housing having a plurality of chambers, a rotor, a speed reduction transmission mechanism and pump arranged in said chambers respectively, and a shaft extending through said chambers alternatively driven by the rotor through said transmission mechanism and driving the pump independently of said transmission mechanism.

3. In a starter, a housing having a plurality of chambers, a rotor, a speed reduction transmission mechanism and pump arranged in said chambers respectively, and a shaft journaled in said housing alternatively driven by the rotor through said transmission mechanism and driving the pump independently of said transmission mechanism, and means for operatively con-

necting said pump to and disconnecting it from said shaft.

4. In a starter, a housing having a plurality of chambers, a rotor, transmission mechanism and a pump arranged in said chambers respectively, a drive shaft actuated by the rotor, a driven shaft actuated from the drive shaft through the medium of the transmission mechanism, one of said shafts having an extension projecting into the pump housing, and means for driving the pump from said extension.

5. In a starter, a housing having a plurality of chambers, a rotor, transmission mechanism and a pump arranged in said chambers respectively, a drive shaft actuated by the rotor, a driven shaft actuated from the drive shaft through the medium of the transmission mechanism, one of said shafts having an extension projecting into the pump housing, and a shiftable clutch carried by said extension for operatively connecting the pump to or disconnecting it from said extension.

6. In a starter, a housing having a plurality of chambers, a rotor, transmission mechanism and a pump arranged in said chambers respectively, a drive shaft actuated by the rotor, a driven shaft actuated from the drive shaft through the medium of the transmission mechanism, said drive shaft having an extension projecting into the pump housing, and means for driving the pump from said extension.

7. In a starter, a housing having a plurality of chambers, a rotor, transmission mechanism and a pump arranged in said chambers respectively, a drive shaft actuated by the rotor, a driven shaft actuated from the drive shaft through the medium of the transmission mechanism, one of said shafts having an extension projecting into the pump housing, an eccentric for actuating said pump free to turn about said extension, and means for coupling said eccentric and said extension together.

8. In a starter, a housing having a plurality of chambers, a rotor, transmission mechanism and a pump arranged in said chambers respectively, a driving sleeve actuated by the rotor having a portion projecting into the transmission chamber, said portion being provided with a gear for actuating the transmission mechanism, a shaft extending through said sleeve and having portions extending into all of said chambers, said shaft being driven through the medium of said transmission mechanism, and a clutch connection between the portion of said shaft arranged in the pump chamber and the pump.

9. In a starter, a housing having partitions dividing the same into a plurality of chambers, a shaft passing through said chambers, bearings for said shaft,

a rotor in one of said chambers, means for admitting compressed air into and exhausting the same from the rotor chamber, a rotor gear sleeved on said shaft projecting into two of said chambers, a gear train and clutch in the second of said chambers for connecting said rotor sleeve with said shaft, said housing including pump cylinder portions, pistons in said cylinder portions, and operative connections between the pistons and said shaft, said connections including a clutch device.

10. In a starter, a rotary fluid-operated motor including a rotor and a shaft, a driving shaft, a driven shaft, a reduction gear train connecting the drive and driven shafts, an air pump including pistons, an eccentric on the driving shaft for operating the pistons, a clutch for operatively connecting the driving shaft and the eccentric, and a single housing inclosing all of said elements and through which the driving shaft extends.

11. In a starter, a rotor and transmission mechanism, a casing inclosing said mechanism and said rotor, a cap inclosing one end of the casing, and a pump casing carried by said cap including cylinders.

12. In a starter, a rotor and transmission mechanism, a casing inclosing said mechanism and said rotor, a cap inclosing one end of the casing, and a pump casing carried by said cap comprising an annular portion having pump cylinders projecting laterally therefrom.

13. In a starter, a housing, a rotor, transmission mechanism, and a pump arranged in said housing, a drive shaft actuated by the rotor, a driven shaft actuated from the drive shaft through the medium of the transmission mechanism, one of said shafts having an extension, an eccentric for actuating said pump loosely rotatable around said extension, a clutch member rotatable with said extension and shiftable into and out of engagement with said eccentric, a piston for said pump, a connecting rod for said piston having a segmental strap engaging said eccentric, and means for holding said strap in engagement with said eccentric.

14. In a self-starter, a combined starting and pumping unit including a starting motor and its shaft connectible with the shaft of the engine to be started, and a housing for inclosing said starting motor and shaft, said unit also including a pumping section, said pumping section including pump cylinders and an annular member secured to said starting section housing, said shaft projecting through said pumping member section, pistons in said pump cylinders, an eccentric mounted for rotation around said shaft, said eccentric having a clutch face, a

shiftable clutch member rotatable with said shaft and shiftable into and out of connection with said eccentric, connecting rods secured to said pistons, and including segmental strap portions engaging said eccentric, the segmental strap portions of one connecting rod being spaced from that of the other connecting rod, and means for holding said segmental strap portions in engagement with said eccentric.

15. In a combined starting and pumping unit, a rotor, a drive shaft, a driven shaft, transmission mechanism intermediate the drive and driven shafts, a pump including pump cylinders and their pistons, one of said shafts having an extension, an eccentric loosely mounted on said extension and including a clutch face, a clutch member mounted to turn with said extension and longitudinally shiftable thereon, including a clutch face to coöperate with the clutch face of the eccentric, connecting rods between said pistons and said eccentric, and means for holding said connecting rods in contact with said eccentric.

16. In a combined starting and pumping unit, a rotor, a drive and a driven shaft, transmission mechanism intermediate the drive and driven shaft, a pump including pump cylinders and their pistons, one of said shafts having an extension, an eccentric mounted to rotate about said extension and including a clutch face, a clutch member mounted on said extension to turn therewith, including a clutch face to coöperate with that of said eccentric, connecting rods for said pistons provided with segmental portions engaging said eccentric, said segmental portions being provided with grooves, and a ring arranged in the grooves in said segmental portions for holding the same in engagement with said eccentric.

17. In a starter, a housing having a plurality of chambers, a rotor, transmission mechanism and a pump arranged in said chambers respectively, a drive shaft actuated by the rotor, a driven shaft journaled in said housing actuated from the drive shaft through the medium of the transmission mechanism, means for driving the pump from one of said shafts, and means for admitting a fluid under pressure to the rotor chamber and exhausting the same.
